ELECTRONIC CURRENT REGULATOR

Charles H. Jones and John H. Thompson, Pittsburgh, Pa., assignors, by mesne assignments, to the United States of America as represented by the Secretary of the Navy

Application August 14, 1953, Serial No. 376,275

1 Claim. (Cl. 323—4)

The invention described herein may be manufactured by or for the Government of the United States of America for governmental purposes without the payment of any royalties thereon or therefor.

This invention relates to a current regulator for continuous wave magnetrons which transmit information by frequency and amplitude modulation.

Both current and voltage regulators have four essential elements in their circuitry, to wit: (1) An electron tube or regulator tube in series with a load whose impedance may vary; (2) An amplifier for amplifying the "corrective" signals; (3) An analyzer for observing the voltage or current (depending upon the type of regulation desired); and (4) A reference voltage for comparison with the analyzed voltage.

It has been found that the voltage current performance curves of continuous wave magnetrons are of such a nature that current regulation provides greater stability than voltage regulation. The present invention, therefore, concerns itself specifically with means to regulate the current.

This invention, although not limited to such use, has been designed primarily for use in connection with an airborne type of radar equipment. One of the essential features is the provision of a light, compact, easily operable type of unit which must, consequently, be as free as possible from bulky, space wasting insulation while, at the same time, it must be non-hazardous to the operating personnel.

In order to achieve the above, this circuit is so devised that the positive side of the regulator output is at ground potential, this characteristic being necessary if the shell or anode of the continuous wave magnetron is to be operated at ground potential. By the use of this circuit, current regulation is possible even with a "shorted" load zero resistance. The arcing or sparking currents which may occur in continuous wave magnetrons due to gas within the tube, mismatch of the load, or inadequate cathode temperature are limited to safe values so that the cathode destruction is minimized. In addition, the composite circuit elements are all operated near ground potential. The regulator amplifier, the voltage reference source, the voltage analyzer, and the current regulator are all kept at safe operating potentials above ground (not over 300 volts). The cathode of the regulator tube is near ground potential and the plate is 1000 volts above ground.

It is, therefore, one object of this invention to provide a current regulator for continuous wave magnetrons which is non-hazardous to operating personnel without the necessity of bulky insulation.

Another object of this invention is to provide a current regulator for continuous wave magnetrons which is light, compact and simple to operate.

Other objects and many of the attendant advantages of this invention will be readily appreciated as the same

becomes better understood by reference to the following detailed description when considered in connection with the accompanying drawing wherein:

Fig. 1 is a schematic diagram of a circuit embodying the invention.

Fig. 2 is a chart showing a regulation curve for a predetermined load current.

Referring now in greater detail to the drawing there is shown a circuit wherein a triode V_1 is used to maintain a constant current across the magnetron. The triode V_1 is in series with the magnetron which has impressed thereon a direct current voltage from a voltage source B. The positive potential of the voltage applied to the magnetron is grounded at G. The cathode of tube V_1 is connected to the anode of the magnetron through resistor R_1 so that the magnetron current must flow through V_1 .

The resistor R_1 plus the magnetron are connected in parallel with a voltage divider network which includes resistors R_2 , R_3 , R_4 and R_5 , a potentiometer R_6 having a capacitor C_1 shunted thereacross, and a pair of gas tubes V_2 and V_3 for regulating the voltage developed across the potentiometer. The potentiometer is connected to the control grid of the pentode V_4 through resistor R_7 , the plate circuit of the pentode having plate resistors R_8 , R_9 , R_{10} and R_{11} . The plate of the pentode is connected to the grid of the tube V_1 in order to regulate the bias thereof. A pair of voltage regulating glow tubes V_5 and V_6 are connected to the screen grid of the pentode V_4 , the anode of tube V_5 being connected to the voltage input through resistors R_{12} , R_{13} , R_{14} , and R_{15} while the cathode of V_6 is at ground potential.

The operation of the system may be understood by assuming that the magnetron impedance decreases slightly. A current increase results from the impedance change and the potential across the resistor R_1 increases. This increase in voltage appears on the control grid of the tube V_4 which, in turn, decreases the grid to ground potential on the tube V_1 . This results in an increase of the grid bias on the tube V_1 which causes a decrease of the space current. In this way, the increase in the load current is almost eliminated. The screen voltage for tube V_4 can be supplied from a low voltage positive supply or it can be connected to the plate at V_2 . Either variation will eliminate the need for R_{12} , R_{13} , R_{14} , R_{15} , V_5 and V_6 . Another modified form of the circuit is to eliminate the R_3 , R_4 and R_5 and connect the cathode of V_3 through the dropping resistor R_2 to a low voltage negative supply (200 or 300 volts). This completely isolates the entire regulating circuit from the high negative voltage.

A regulation curve is shown in Fig. 2 for a load current adjustment of 150 milliamperes and various load voltages which were obtained by varying the load resistance. The internal effective impedance is greater than 20 megohms.

Obviously many modifications and variations of the present invention are possible in the light of the above teachings. It is, therefore, to be understood that within the scope of the appended claim the invention may be practiced otherwise than as specifically described.

What is claimed as the invention is:

1. A current regular network for a load circuit having a pair of input terminals said network comprising a high voltage supply source having a positive terminal and a negative terminal; means connecting one of the input terminals of the load circuit to the negative terminal of the supply source; means connecting the other input terminal of the load circuit to ground; a first electron tube having an anode, a cathode, and a control grid; a first

resistor; means connecting the anode of the first electron tube to the positive terminal of the supply source; means connecting the cathode of the first electron tube to ground through the first resistor; a second electron tube having an anode, a cathode, and a control grid; means coupling the cathode of the first electron tube to the control grid of the second electron tube; means connecting the cathode of the second electron tube to ground; a second resistor; means connecting the anode of the second electron tube to the positive terminal of the supply source through the second resistor; and means also connecting the anode of the second electron tube to the control grid of the first electron tube.
